J. PENROD ET AL

PUMP FOR WELLS

Filed March 23, 1926

UNITED STATES PATENT OFFICE.

JOHN PENROD AND ROBERT D. THOMPSON, OF OKMULGEE, OKLAHOMA.

PUMP FOR WELLS.

Application filed March 23, 1926. Serial No. 96,807.

- This invention relates to pumping equipment for use in wells and more particularly to a means for flushing a special sand receiving chamber of the pump, so that the sand present in the chamber is returned to the bottom of the well for mixing with the fluid therein whereby the subsequent operation of the pump will carry the sand off in suspension.
- Our application Serial No. 696,191, filed March 1, 1924, disclosed a well pump having a special sand receiving chamber, the bottom of which may be opened for the dumping of the sand in the special sand receiving chamber, but there is a possibility that the sand will tightly pack in the chamber to form a barrier between the column of fluid above and the opening whereby an effective flushing action is prevented.
- It is, therefore, an important object of this invention to provide a pumping equipment in which the sand receiving chamber may be opened at the bottom thereof and communication positively established between the opening and the column of fluid above so that a portion of the fluid above may wash down through the chamber and break down the body of tightly packed sand therein to bring about the effective flushing and cleansing of the sand receiving chamber, the sand thus flushed out of the chamber being returned to the bottom of the well and subsequently pumped out with the fluid.
- Other objects and advantages will be apparent during the course of the following description.
- In the accompanying drawing forming a part of this application and in which like numerals are employed to designate like parts throughout the same,
- Figure 1 is a vertical sectional view through a pumping mechanism equipped with the improved sand pump;
- Figure 2 is a detail sectional view illustrating the pumping mechanism in sand dumping position;
- Figure 3 is a similar view illustrating the parts in normal operating position;
- Figure 4 is a sectional view illustrating a modification of the invention.
- In the drawing the numeral 5 designates a
- tubing to which a shell 6 is connected by means of a bushing 7. The lower end of the shell 6 has connection with what might be said to be a combined connector, spring housing and valve seat 8, provided with an annular groove 9. The annular groove 9 is V-shaped in cross section and the walls of the same are adapted to be engaged by the upper edges of an annular valve 10 whereby a fluid-tight connection is established between the members 8 and 10. The upwardly directed valve 10 is in the nature of a flange on the outer edges of a shoulder 11 formed on the lower end of a standing valve unit 12 supporting member 12.
- In carrying out the invention, the standing valve unit supporting member 12 has connection with the lower end of a barrel 14 through the medium of a coupling 16. The internal diameter of the barrel 14 is substantially the same throughout, but the external diameter of the barrel gradually decreases toward the upper end thereof, so that when the barrel is lowered slightly by a means to be fully described, a fluid passage will be formed between the barrel and the wall of sand. The fluid passage thus formed will allow of the movement of the fluid past the sand collected in the chamber defined by the members 6 and 14. The movement of the fluid in contact with the unsupported side wall of the sand will immediately break down the tightly packed body of sand and thereby bring about the return of the sand to the well. In other words, the pocket for the sand is thoroughly flushed and cleansed by the movement of the fluid therethru.
- Before proceeding with the description of other parts of the invention, it is desired to emphasize that the working barrel is movably positioned within the shell, and when the same is lowered the external taper of the barrel results in the formation of an annular fluid passage about the barrel and it is through this passage that the fluid may wash to break down the body of tightly packed sand. This dumping operation may take place several times a day or as often as circumstances require.
- The external taper of the working barrel may be uniform throughout, or the taper

may continue only to a point near the center thereof and the remaining portion of the barrel allowed to be the same diameter throughout.

5 The standing valve unit 12 is extended through the combined spring housing, connector and valve seat 8 and carries a standing valve unit 20 against the cage of which, the lower end of a plunger 21 may be engaged to unseat the valve 10 and thereby bring about a sand return opening and a fluid passage between the working barrel and the packed sand through which the fluid may wash to effectively disintegrate the sand and cause its return to the well.

10 The valve supporting unit 12 and the valve 10 of the same are normally maintained in elevated position as shown in Figure 3 by a helical spring 24 engaged with the under-
20 side of the shoulder 11 and mounted on a spider 26. The spider is in turn mounted on the top of a washer 28 and the washer may rest on the upper end of one of the sections 30 of the anchor.

25 It is important to note that the effective strength of the spring 24 may be increased or diminished by varying the thickness of the washer 28. If the improved dumping mechanism is employed in a deep well where
30 the column of fluid to be more or less constantly supported is of a substantial weight, a thick washer 28 may be employed to increase the force exerted by the spring. Therefore, the strength of the spring will normally overcome the weight of the column of fluid and will maintain the valve 10 seated. However, when the normal stroke of the plunger 21 is intentionally exceeded by the operator, the parts will assume the
40 position illustrated in Figure 2 and a fluid passage will be formed between the barrel 14 and the body of sand through which the fluid may wash to break down the body of sand and thereby quickly return the same to
45 the well so that pumping may be resumed without a substantial loss of fluid. Another important advantage resides in the fact that no time is lost in pulling the tubing and other equipment to the surface for removing the sand collected in the sand receiving chamber.

50 When the plunger is engaged with the valve unit 20 as shown in Figure 2 the weight of the plunger and the rods of the same will overcome the strength of the spring 24 and the spring will be compressed. The compression of the spring, however, is limited by the engagement of the shoulder 11 with the upper end of a tubular stop member 33. The stop member may be mounted on the
55 spider 26. This arrangement greatly protects the spring.

60 The gas anchor consists of the outer section 30 and an inner tubular section 38, the lower end of the inner section 38 being above the lower end of the outer section as suggested

in Figures 1, 2 and 3. It is shown in the drawing that the spring housing 8 has an opening 40 while the inner section has an opening 41, both of these openings being adjacent the upper ends of the gas anchor for
70 the passage of gas.

Coming now to the fluid inlet, it will be seen that the outer section may be provided with a series of openings 46 for the admission of fluid and that the lower end of the section 38 is below the openings 46, but closer to these openings than to the lower end of the outer section 30.

75 In the form of invention shown in Figure 4, the valve 50 at the lower end of the sand receiving chamber has a beveled contact portion engaged with the inner edge of an annular valve seat 51 of a combined connector, spring housing and valve seat 52. The other parts of this form of the invention are substantially the same as the form
80 illustrated in Figures 1, 2 and 3.

85 In the several forms of invention illustrated the standing valves and more specifically the cages thereof are enclosed within the working barrels and constitute striking or contact elements for engagement by the lowering mechanism, the lowering mechanism being illustrated in the forms of plungers 21. Special attention is invited to the fact that the working barrel not only functions as such and as one wall of the chamber, but also as a means to space the sand in the sand receiving chamber from the working barrel so that the standing valve is at all times exposed to the action of the plunger.

90 Having thus described the invention, what is claimed is:

95 1. In a pump, the combination of a working barrel, a shell receiving the working barrel and being spaced therefrom to define a sand receiving pocket, means movably supporting the barrel, and a valve for said pocket movably supported by said means.

100 2. In a pump, the combination of a barrel, a shell receiving the barrel and being spaced therefrom to define a sand receiving chamber, a valve for the discharge of sand from said chamber, and means movably supporting said valve and said barrel, one wall of the chamber being tilted to enlarge the chamber toward one end.

105 3. In a pumping equipment, a barrel, a shell receiving the barrel and being spaced therefrom to define a sand receiving pocket, a valve for the discharge of sand from said pocket, a spring normally closing said valve and supporting said barrel in an elevated position, said barrel being provided with means whereby a space is formed between the barrel and the sand when the barrel is lowered.

110 4. In a pump, the combination of a longitudinally movable working barrel, a sand discharge valve rigidly connected to and
115

movable with the working barrel, a housing having a valve seat adapted for engagement by said valve, a spring within said housing and normally seating said valve and urging said working barrel to an extreme position, and means limiting the compression of the spring.

5. In a pumping equipment, a shell, a combined coupling and valve seat member secured to the shell and having a groove defining a valve seat, a member having a shoulder and a valve, the valve being adapted to engage said seat, a standing valve connected to said member, a spring engaged with said shoulder to normally seat said first named valve, a support for said spring, and means whereby the movement of the spring is limited.

6. The construction set forth in claim 5, and a barrel connected to said member and being within said shell to cooperate with the shell in defining a sand pocket.

7. In a pumping equipment, the combination of a shell, a member at one end portion of the shell and having a seat, a valve member having a contact portion to engage said seat, a barrel connected to said valve and being movable therewith, and a spring normally supporting said valve and said barrel in elevated position.

8. The construction set forth in claim 7, and means whereby the movement of the spring is limited.

9. In a pump, the combination of a pair of cooperating interfitting tubular members spaced to define a sand receiving chamber, means whereby one member may be moved out of supporting engagement with the sand in said chamber, and a discharge valve for said chamber, one wall of said chamber being extended at a slight angle to the axis of the chamber.

10. In a pump, the combination of a shell, a working barrel therein and cooperating therewith in the formation of a sand receiving chamber, a discharge valve for said chamber, one wall of said chamber being at a slight angle to the axis of the chamber.

11. In a pump, the combination of a shell, an externally tapered working barrel therein and cooperating therewith in the formation of a sand receiving chamber, a discharge valve for said chamber, said externally tapered working barrel being movably mounted within the shell whereby the same may be moved out of retaining relation to the sand in said chamber.

12. In a pump, the combination of a shell, a working barrel within the shell and cooperating therewith in the formation of a sand receiving chamber, said working barrel being externally enlarged at one end and normally in retaining relation to one wall of the sand in the chamber, and means whereby the externally enlarged portion of said

working barrel may be moved out of retaining relation to the sand in said chamber.

13. In a pump, the combination of a shell, a working barrel within the shell and cooperating therewith in the formation of a sand receiving chamber, said working barrel being externally enlarged at one end and normally in retaining relation to one wall of the sand in the chamber, means whereby the externally enlarged portion of said working barrel may be moved out of retaining relation to the sand in said chamber, and a sand discharge valve associated with said working barrel.

14. In a pump, a movable support having a contact element adapted to be engaged by a striking unit, a pair of interfitting tubular members spaced to define a sand receiving chamber, one of said tubular members being mounted on said movable support and constantly enclosing said contact element to constantly expose the same to the striking unit and to space sand in said chamber from said contact element.

15. In a pump, a stationary and a movable tubular member arranged one within the other to provide an intervening sand receiving chamber, means operable by the movable member to close and open the lower end of the chamber, and means normally holding the movable member against movement.

16. In a pump, a stationary and a movable tubular member arranged one within the other to provide an intervening sand receiving chamber, the movable member being formed to provide a space between it and the sand on its movement with respect to the other member, means operable to close and open the lower end of the chamber, and means normally holding the movable member against movement.

17. In a pump, a stationary and a movable tubular member arranged one within the other to provide an intervening sand receiving chamber, the movable member being tapered to provide a space between it and the sand on its movement with respect to the other member, means operable to close and open the lower end of the chamber, and means normally holding the movable member against movement.

18. In a pump, a stationary and a movable tubular member arranged one within the other to provide an intervening sand receiving chamber, the movable member being formed to provide a space between it and the sand on its movement in one direction with respect to the other member, means closing the lower end of the chamber and operable by the movable member when moved in said direction to open the lower end of the chamber, and means normally holding the movable member against movement.

19. In a pump, an outer tubular member, an inner tubular member spaced from the outer tubular member to provide an intervening sand receiving chamber, the inner member being tapered and movable axially with respect to the outer member, means operable by the movable member to close and

open the lower end of the chamber, and means normally holding the movable member against movement.
